Primary Examiner — Prabhakar G Deshmukh(74) *Attorney, Agent, or Firm* — Banner & Witcoff, Ltd.(57) **CLAIM**

The ornamental design for a mosaic tile, as shown and described.

DESCRIPTION

FIG. 1 is a front view of a mosaic tile showing my new design;

FIG. 2 is a front isometric view thereof;

FIG. 3 is a left side view thereof;

FIG. 4 is a right side view thereof;

FIG. 5 is a top view thereof; and,

FIG. 6 is a bottom view thereof.

The broken line showing of the webbing connecting the individual tiles and the non-front surfaces of the tiles represents unclaimed subject matter and forms no part of the claimed design. The contrast in shading represents a contrast in appearance only and does not represent any particular color, texture or finish.
